UNITED STATES PATENT OFFICE.

CHARLES D. THOMPSON, OF WASHINGTON, DISTRICT OF COLUMBIA.

COMBINED PENCIL AND MISCELLANEOUS HOLDER.

Application filed October 29, 1926. Serial No. 145,024.

The primary purpose of this invention is to supply a holder to be attached to a type-writing machine for receiving pencils, erasers and sundry articles which it is desirable for a typist to have ready and conveniently at hand for instant use.

The invention provides an article of the nature aforesaid which may be cheaply manufactured and which is light and free from joints and which embodies a tray for miscellaneous articles, a coil to receive and hold pencils and a clamp for attachment of the device to the typewriting machine.

While the drawings illustrate a preferred embodiment of the invention, it is to be understood that in adapting the means to meet specific needs and requirements the design may be varied and such other changes in the minor details of construction may be resorted to within the scope of the invention as claimed, without departing from the spirit thereof.

For a full understanding of the invention and the merits thereof, reference is to be had to the following description and the drawings hereto attached, in which,—

Figure 1 is a side view of the device showing it applied to a typewriting machine.

Figure 2 is a top plan view of the device showing a portion of the typewriter frame to which it is fitted, the dotted lines indicating the position of a pencil.

Figure 3 is a detail sectional view on the line 3—3 of Figure 2, looking in the direction of the arrows.

Figure 4 is a schematic view of the blank from which the article is formed.

Corresponding and like parts are referred to in the following description and designated in the several views of the drawings by like reference characters.

The device comprises a tray, an attaching clamp, and a pencil holder, the latter consisting of an open coil spring.

The jaws of the clamp, the tray and the supporting elements for the coil spring are of integral formation and comprise parts of a single blank having the outline substantially as illustrated in Figure 4 of the drawings, said blank having portions folded upon itself, as indicated by the dotted lines to provide the several elements.

As indicated most clearly in Figure 4, the blank comprises an elongated, or strip portion, and a lateral extension at one end thereof, from which the tray is formed, the

elongated or strip portion forming the jaws of the clamp and the supporting means for the wire coil constituting the pencil holder. The lateral extension of the blank constitutes the bottom 1 of the tray, the ends 2 and the side 3. The portions 2 and 3 are bent perpendicular to the bottom portion 1 along the dotted lines. The end portions 2 project a short distance so as to overlap the ends of the side 3, as indicated most clearly in Figure 2. The strip or elongated portion of the blank comprises a portion 4 which constitutes the bottom of the support for the pencil holding coil 5, portions 6 which when folded, provide the inner jaw of the clamp, portions 7, similar to the portions 6, which when folded, provide the outer jaw of the clamp, an intermediate portion 8 connecting the two jaws, a portion 9 overlying the clamp and similar end portions 10 which are bent upwardly to form the end pieces between which the pencil holding coil 5 is confined and retained in place by ears 11 at the extremities of the strip or elongated portion of the blank and bent over the end coils of the pencil holder 5, as shown most clearly in Figure 3 of the drawings. The portions 6, when folded, lie close together and are apertured to receive a clamp screw 12 which is threaded into the opening and provided at its inner end with a pressure piece 13 connected thereto by means of a swivel joint to admit of rotation of the clamp screw without a corresponding rotary movement of the pressure piece. The portions 7 of the blank lie close together, as indicated most clearly in Figure 3.

The spring coil 5 constitutes a rack or holder for pencils and analogous articles, and is supported upon the part 4 and confined between the parts 10 and is retained in place by having the ears 11 bent over the end coils. The inner or rear side of the tray is open, however, the coil 5 extends across said open side and prevents displacement of articles placed upon the tray. The clamp is located wholly at one side of the tray and pencil holder, or rack, thereby spacing the same from the typewriter to prevent interference with manipulation of the keys thereof, while at the same time being readily accessible for convenient support of the articles to be kept readily at hand for immediate use.

While the device is particularly adapted for typewriting machines, it may be em-

ployed in connection with other objects, whereby to maintain pencils, erasers, paper clips and the like in convenient position for the use of a typist, accountant or amanuensis.

5 The clamp provides convenient means for attaching the device to the frame of a typewriter or to any other desired support.

Having thus described the invention, I claim:

- 10 1. A combined holder of the character specified comprising a tray adapted to receive erasers and sundry small articles, a pencil holder in line with and forming a side of the tray and a clamp at one side of the tray and pencil holder to space the same from a typewriting machine or other support, to which the article may be attached.
- 15 2. A device of the character specified comprising a tray closed at one side and opposite ends by upstanding walls and a pencil holder at the open side of the tray including a wire coil extending across the open side of the tray to prevent displacement of articles from the said open side of the tray.
- 20 3. An attachment for typewriting machines comprising a tray having an open side and an extension at the open side provided with upwardly projecting elements, a pencil holding coil closing the open side of the tray and supported upon the said extension and connected to the upwardly projecting elements thereof, and a clamp in line with and at one end of said extension.
- 25 4. A combined device of the character specified, comprising a tray, a support at one side of the tray comprising a bottom and end pieces, a wire coil resting upon the bottom portion of the support and confined between the end pieces thereof, and a clamp in line with the support to space it and the tray from the part to which the device may be attached.
- 30 5. A device of the character specified comprising a single blank including a strip and a lateral extension at one end of the strip, a side and end portions of the lateral

extension being bent to form enclosing walls of a tray and the said strip having portions bent to provide a support and spaced depending jaws, said support including a bottom and end pieces, a clamp screw fitted to one of said jaws and an open wire coil confined between the end pieces of the support and resting upon the bottom portion thereof, parts of the end pieces being bent around the end coils to retain the said open coil in place.

6. A device of the character specified comprising a single blank including a strip and a lateral extension at one end of the strip, said lateral extension having a side and end portions bent to form enclosing walls of a tray, and the said strip having portions folded to provide spaced jaws of a clamp and end pieces of a support, the bottom of which is substantially in the plane of the bottom of the tray, said strip having terminal ears, and an open wire coil placed upon the bottom of said support and confined between the end pieces and retained in place by having the said ears bent about the end coils, and a clamp screw fitted to one of the jaws of the clamp.

7. A device of the character specified, comprising a single blank including a strip and a lateral extension at one end of the strip, a side and end portions of the lateral extension being bent to provide enclosing walls of a tray, and said strip having intermediate portions folded to provide spaced jaws of a clamp and having end portions bent to provide end pieces of a support, said strip having terminal ears, an open wire coil confined between the end pieces of the support and resting upon that portion of the strip opposite and in line with the tray, and having the said ears bent about the end coils thereof, and a clamp screw fitted to one of the jaws of the clamp.

In testimony whereof I affix my signature.

CHARLES D. THOMPSON. [L. s.]
